UNITED STATES PATENT OFFICE

97,944

DESIGN FOR A WATER HEATER

Herbert J. Long, Springfield, Mass., assignor to United American Bosch Corporation, Springfield, Mass., a corporation of New York

Application October 9, 1935, Serial No. 58,896

Term of patent 7 years

To all whom it may concern:

Be it known that I, Herbert J. Long, a citizen of the United States, residing at Springfield, in the county of Hampden, State of Massachusetts, have invented a new, original, and ornamental Design for Water Heaters, of which the following is a specification, reference being had to the accompanying drawing, forming a part thereof.

The figure is a front perspective view of a water heater showing my new design. The rear surface is substantially plain.

I claim:

The ornamental design for a water heater, as shown and described.

HERBERT J. LONG.
